UNITED STATES PATENT OFFICE.

CHARLES H. SCHOPBACH, OF AURORA, ILLINOIS, ASSIGNOR TO INTERNATIONAL CORSET COMPANY, OF AURORA, ILLINOIS, A CORPORATION OF ILLINOIS.

CORSET.

Application filed December 24, 1920. Serial No. 432,993.

To all whom it may concern:

Be it known that I, CHARLES H. SCHOPBACH, a citizen of the United States, residing at Aurora, in the county of Kane and 5 State of Illinois, have invented certain new and useful Improvements in Corsets, of which the following is a specification, reference being had to the accompanying drawings, and to the reference characters marked 10 thereon, which form a part of this specification.

This invention relates to improvements in corsets and the main object of the invention is to provide an improved insert for a corset 15 which is suitably stiffened and supported in the front and at the same time, provided with flexible means at the upper front portion which yields readily to conform to the contour of the figure and also as the wearer 20 may bend or move the body, thus avoiding discomfort to the wearer.

My invention comprises the making of a stay strip of metal sufficiently thick and stiff to perform its intended function as a 25 stiffening stay, which strip shall not extend to the top edge of the corset, and in applying thereto at its upper end, one or a plurality of relatively thin, flexible, shorter metal strips which extend from the first 30 mentioned strip to substantially the top margin of the corset.

The further objects and advantages relating to the structural details of my invention will more definitely appear from the 35 following description of the preferred embodiment of the invention illustrated in the accompanying drawings.

In said drawings:

Fig. 1 illustrates in a front elevation, a 40 portion of a front lace, front opening corset, embodying my invention.

Figs. 2 and 3 are views, in front elevation, of two metal stay strips, with the flexible metal strips attached.

Fig. 4 is an end elevation of the metal strip shown in Fig. 3.

Fig. 5 is a view of the cloth covering for the upper end of the flexible metal strips, as indicated by the dotted lines in Figs.

50 2 and 3.

Fig. 6 is a transverse, sectional view of the cloth cover shown in Fig. 5, taken in the plane of the line 6—6 of Fig. 5.

Fig. 7 is a vertical, sectional view of one of the corset stays, the same being taken in 55 the plane indicated by the line 7—7 of Fig. 1.

Fig. 8 is a vertical, sectional view of the same, taken on the plane indicated by the 60 line 8—8 of Fig. 7.

Fig. 9 is a plan view of a piece of cloth to which certain hooks are secured. Fig. 10 is a similar view of a piece of cloth to which certain eyes are attached.

Fig. 11 is a transverse, sectional view 65 through a pair of corset stays at the front of the corset, the section being taken on the plane indicated by the dotted line 11—11 of Fig. 1. Fig. 12 is a similar sectional view taken in the plane indicated by the dotted 70 line 12—12 of Fig. 1.

Fig. 13 is a similar view taken in the plane indicated by the dotted line 13—13 of Fig. 1, broken away, for convenience in drawing, at the right hand portion. 75

In the drawing, A represents one of the two front body sections of a corset, its front edge being provided with one of a pair of stays indicated as a whole by the letter B. The other corset stay which is removably 80 secured to the stay B is indicated as a whole by the letter C. D indicates the usual lacings which unite the stay C through a series of eyelets e with a front stay (not shown) on the front margin of the other 85 body section of the corset, in a familiar manner.

As shown in the drawings and more particularly in Figs. 1, 2, 5, 6, 10, 11, 12 and 13, the stay B is constructed as follows: A 90 metal stiffening body or insert strip 1, of such length as not to extend the full length of the front of the corset, is provided with a plurality of eyelet members 2 of the corset clasps, said clasp members 2 being shown 95 as riveted to the metal stiffening insert strip 1, at 3. The strip 1 is covered with an envelope 4 of any suitable material, but preferably of paper. The enveloping material is usually wrapped about the insert 1 before 100 the clasp members 2 are secured thereto.

At the upper end of the body or insert strip 1 are shown a plurality of shorter metal strips, 5, 6, 7, of different lengths, each being riveted to the insert strip 1 by the rivet 105 8. This is the preferred construction of this

improved stay member, but manifestly, the strip 5, or the strip 6, may be omitted. The strip or strips 5, 6, 7, are covered with a suitable enveloping material 9, preferably of fabric folded longitudinally and stitched as indicated at 10, to form a pocket 11, which pocket encloses the strip or strips. The enveloping fabric 9 has a flap portion 12 in addition to the pocket 11. The metal member thus described and shown in Fig. 2, enclosed as hereinabove described, is then inserted within a pocket 13 formed in the margin of the front of the body section A in the usual manner. That is to say, a strip 14 of cloth 14 is folded upon itself as shown more clearly in Fig. 12, and then the fabric *a* is folded about this cloth 14 and its extreme end portion 15 tucked around the inner end 16 of the fabric 14, and the two 20 united by rows of stitching 17, 17, the clasp members 2 projecting at intervals through the margin *a* as indicated in Figs. 1 and 12. Of course the pocket 13 to hold the enveloped metal insert stay may be formed in 25 any other suitable manner. The essential requirement, however, is that the metal insert strips shall be so placed in the pocket that the flexible strips 5, 6, 7, attached thereto shall lie to the inside of the corset so as 30 to bend outwardly when bending is required. Where three strips, 5, 6, 7, are used, the strip 7 is placed nearest the body of the wearer, the strip 5 toward the outside of the corset, and the strip 6 intermediate the two. It 35 will be noted also that the top of the flexible strip 7 is near the top *b* of the corset; that the rivet 8 is near the top of the insert strip 1 and also that the lower end 18 of the body or insert strip 1 does not extend to the lower 40 edge of the corset, as shown by the cut-away portion, Fig. 1.

Referring now to Figs. 3, 4, 7, 8, 11, 12 and 13, it will be seen that the other front stay member C is composed of fabric with a 45 stiffening member and lacing eyelets arranged in three longitudinal sections; the outer or marginal section comprising a pocket 19, the inner marginal section a pocket 20, and the intermediate section providing for the lacing eyelets, *c*. Within the 50 pocket 19, I place a metal insert strip with a flexible upper end made in all respects similar to the insert strip 1, previously described, with the exception that instead of 55 the eyelet clasp member 2, a stud member 21 is used. It will be manifest, of course, that the two parts 21 and 2 together form a corset clasp and function in a familiar manner.

60 Within the pocket 20 I place a relatively flexible stiffening member 22 of featherbone or thin metal, or other suitable material. The fabric of which the stay strip C is composed may be folded and stitched in any 65 convenient manner, as for example, the man-

ner indicated in Figs. 11, 12 and 13. In order to secure the adjacent margins B', C', of the stay members B, C, together, at points both above and below the metal strips 1, I use hooks and eyes, indicated at 23, 23'. These hooks and eyes are respectively riveted to strips of cloth, 24, 25, as indicated by the rivets 26. The strips of fabric, 24, to which the hooks are secured, are preferably secured to the stay C by the eyelets *c*; and the fabric strips 25 may be secured to the fabric *a* by the rows of stitches 17. The flap extension member 12 of the envelope 9 that surrounds the flexible strip or strips 5, 6, 7, may be secured to the stay member B by the rows of stitching 17, and the corresponding flap member in the said member C may be secured thereto by the eyelets *c* or by the rows of stitching which form the pocket 20, or both.

When the parts thus described are secured together, the corset placed upon the wearer, and the stays B and C united by means of the hooks and eyes 23, 23', and the clasp members 2, 21, it will be found that the central portion of the front of the corset will possess the necessary strength and stiffness by reason of the relative rigidity of the metal insert strips 1, while the upper portion thereof will flex and bend readily to conform to the contour of the body of the wearer and to any bending or other movement of the wearer; that this bending and flexure will not produce any discomfort to the wearer, or cause the breaking of the metal parts; and, furthermore, that the construction is such that the flexible members attached to the insert strips 1, will immediately resume their normal position when the wearer resumes her natural position. As illustrated in Fig. 11, the hooks 23' and the eyes 23 are secured to strips of cloth, 24 and 25, respectively. It will be manifest that their positions on the parts B and C are such as to afford the necessary and desirable relative movement or play between said hooks and eyes, when the latter are engaged, whereby said hooks and eyes, when engaged, do not interfere with the free movement under flexure of the upper portions 5, 6 and 7, of the metal insert strip 1. It will be clear that the hooks and eyes are not attached directly to the strips 1, but to the edge of the pockets enclosing said strips. By reason of this flexible connection and of the flexible connection between each hook and eye, and also, because of the flexibility due to what may be called the swiveling movement in a horizontal plane between each eye and its associated hook, movement of one stay to a limited extent independently of the other stay, is permitted. To the movement which is permitted between each hook, and its eye, is added the swing allowed because of the flexibility of 130

the material of which the pockets are formed. Thus a corset is produced which gives great comfort to the wearer and yet performs its intended function of supporting the body, throughout the lifetime of the garment as a whole.

It will be understood, of course, that the stay member attached to the other margin of the corset body to which the lacings D are secured, will be made precisely similar to the stay section C, but without the stud members and the hooks,—that is to say, it will contain a pocket provided with a metal stay insert strip 1, having one or a plurality of shorter and relatively thinner, flexible strips riveted to the upper end thereof, to correspond to the stay members B and C.

It will also be understood that the thin strip or strips 5, 6, 7, should be secured 20 to the strip 1 in such manner as to be in prolongation of the latter and not have any tendency to sidewise movement with respect to the strip 1. In other words, so secured as to remain in the pocket 20 and 25 form a relatively firm abutment to resist the tension on the stay C by the pull and strain of the lacings. This will normally be effected by the single rivet 8 shown, but manifestly equivalent fastenings (as for 30 example, two rivets) may be used.

I claim as my invention:

1. An insert for corsets comprising a relatively rigid body portion and a plurality of strips attached to and forming a prolongation of said body portion and of greater flexibility than the latter, said insert being provided with clasp members upon its rigid body portion only.

2. An insert for corsets comprising a relatively rigid body portion and a plurality of strips attached to and forming a prolongation of said body portion, said strips

being arranged in overlapping relation each to each, and of greater flexibility than said body portion, said body portion being provided with clasp members, and said strips being free of clasp members.

3. A corset provided with a vertically extending pocket adjacent each of its meeting edges, an insert in each pocket, of more resiliency at its top portion than at its bottom portion, co-operating clasp members secured to the lower portions of said inserts, and extending through the material of the pockets for mutual engagement, and fastener members secured to the material of one pocket, adjacent the upper portion of said insert but disconnected therefrom, and adapted for co-operative engagement with co-operating fastener members secured to the material of the opposite pocket, substantially as described.

4. A corset provided with a vertically extending pocket adjacent each of its meeting edges, an insert in each pocket comprising a relatively rigid body portion provided with corset clasps rigidly secured thereto, a plurality of resilient strips of different length, free from clasp members, positioned one upon the other and secured to said insert so as to project beyond the end and in prolongation thereof, the longest of said strips being nearest the longitudinal center of the corset, substantially as described.

In testimony that I claim the foregoing as my invention I affix my signature, in the presence of two witnesses, this 18th day of December, 1920.

CHARLES H. SCHOPBACH.
